DESIGN FOR A BUFFET PLATE

Arthur Brandes, Los Angeles County, and Frank
W. Jordan, La Habra, Calif.

Application February 13, 1939, Serial No. 82,968

Term of patent 3½ years

To all whom it may concern:

Be it known that we, Arthur Brandes and Frank W. Jordan, citizens of the United States and residing in the county of Los Angeles and State of California, and La Habra, in the county of Orange and State of California, have invented a new, original, and ornamental Design for a Buffet Plate, of which the following is a specification, reference being had to the accompanying drawing, forming a part thereof.

In the drawing:

Fig. 1 is a top plan view of the article showing our design; and

Fig. 2 is a sectional view taken on line 2—2 of Fig. 1.

We claim:

The ornamental design for a buffet plate, as shown.

ARTHUR BRANDES.
FRANK W. JORDAN.
